HENRY CLINTON BALDWIN, OF LAKEMONT, NEW YORK, ASSIGNOR OF ONE-HALF TO
NED E. BALDWIN, OF LAKEMONT, NEW YORK.

TOY.

1,115,272.

Specification of Letters Patent. Patented Oct. 27, 1914.

Application filed August 19, 1913. Serial No. 785,549.

To all whom it may concern:

Be it known that I, HENRY C. BALDWIN, a citizen of the United States, and a resident of Lakemont, in the county of Yates and State of New York, have invented a new and Improved Toy, of which the following is a full, clear, and exact description.

The invention relates to a toy windmill, and it is a design of the invention to provide an attractive toy of the indicated character, and one that may be made to serve the purpose also of a weathervane.

It is a further design of the invention to provide a windmill toy so constructed with regard to the frame, bearings, etc., that the device will operate even in an exposed place for a long period without attention or repairs.

It is a further design of the invention to provide a toy of the indicated character in which a single piece of wire is formed to constitute the frame having a shaft or axle about which the wind wheels revolve, a socket or sleeve for a suspension rod, and to provide means for the connection of the weather vane.

The invention will be particularly explained in the specific description following.

Reference is to be had to the accompanying drawings forming a part of this specification, in which similar characters of reference indicate corresponding parts in all the views.

Figure 1 is a perspective view of a toy windmill embodying my invention; Fig. 2 is a detail side elevation, partly in section; and Fig. 3 is a front view of one of the wind wheels.

In constructing a toy in accordance with my invention, a single piece of wire is formed into a close spiral coil 10 between its ends, and one end is carried horizontally to constitute a shaft or axle 11, mounted loosely on which are two or more wind wheels 12. The wind wheels are separated by a spacing sleeve 13 on the axle 11 between the wheels, and the elongated collars or short sleeves 14 are also provided on the axle outside of the wheels, the connection being completed by a nut or collar 15 on the end of the axle.

From the opposite end of the coil 10 the wire is formed into a loop, being first carried out horizontally, as at 16, then upwardly to provide a vertical member 17, and returned,

as at 18, toward the coil, and finally bent downwardly, as at 19, to provide a second vertical member parallel with the outward vertical member 17. The vertical members 17, 19, serve for the connection of a vane or tail 20, which is secured by a strap 21, said strap being returned on itself centrally, and formed into a parallel sleeve 22 embracing the inner vertical member 19, and then brought against the opposite sides of the vertical member 17, the extreme ends being overlapped on the vane 20 and soldered or otherwise securely fastened thereto.

The sleeve 10 receives a hanger rod 23, which passes freely through the sleeve and is provided with a nut or collar 24 on which the sleeve rests, whereby to suspend the wire frame, the wind wheels and the vane, so that they may turn about the suspension rod 23 as an axis, in response to changes in the wind. The suspension rod is formed in sections, there being two sections 23, 24, as shown in the drawings, the upper one having a suitable eye 25 or equivalent means whereby to suspend the toy from an overhead support either indoors or outdoors. The number of sections may be increased or diminished to vary the length of the hanger to support the wheels and vane at any desired height.

Interposed between two of the hanger sections is a panel 26, which may be made to bear an advertisement. In any case the hanger is articulated so that the frame carrying the wheels and vane may sway in the wind or forced current of air, thus increasing the attractiveness of the toy.

Each wheel 12 is formed in practice, of sheet metal and for the main part is preferably made in a single piece; thus the various blades 27, there being four blades on each wheel in the illustrated example, are formed integrally with a center or sheet metal hub portion 28, having a bearing hole 29 for the shaft or axle 11. The hub may be completed by a separate, hollow member or three-sided box 30 having a hole alining with the hole 29 to slip over the axle, the box being soldered or otherwise secured at its ends to the hub portion 28, as best seen in Fig. 2. Each blade 27 is bent longitudinally on a diagonal line, indicated at 31, the inner end of the blade being separated from the hub portion 28, as indicated at 32 in Fig. 1. The bending of the blade gives it

an angular form in cross section sufficient to take the air current and cause the wheels to revolve. The blades of the two wheels are bent oppositely so that the wheels will revolve in opposite directions.

The construction described enables me to produce a toy at a minimum cost, while making it durable and attractive.

It may be mentioned that the lower end 10 of the lower sections 23 of the suspension hanger may be secured upright on a post or other support, the upper elements of the suspension means being detached.

Having thus described my invention, I claim as new, and desire to secure by Letters Patent:

1. A toy of the character described, comprising wind wheels, a rod forming at one end an axle on which the wheels are mounted to turn, said rod at one end of the axle being formed into a spiral, vertical coil constituting a bearing, a hanger rod passing loosely through said coil, a member on the rod supporting the coil, the said rod at the end of the coil opposite to the axle being extended outwardly in the form of an arm diametrically opposed to the axle, the rod further more having three successive bends at right angles to form with the said arm four sides

of a rectangular frame, the last mentioned bend presenting a member parallel with the coil, and adjacent to the latter, a vane disposed at the end of the frame opposite to the coil and axle, and a strap securing the vane to the frame, said strap being returned on itself, presenting separate side members, the ends of the members overlapping and being secured to opposite sides of the vane, and extending therefrom at the sides of the rectangular frame and being bent around that member of the said frame adjacent to the coil, between the said coil and said adjacent frame member.

2. A toy windmill comprising a frame having a wheel mounted to turn and provided with a vane, a hanger on which said frame is adapted to turn in a horizontal plane, the hanger being formed in separate sections, and a panel interposed between and connecting the hanger sections.

In testimony whereof I have signed my name to this specification in the presence of two subscribing witnesses.

HENRY CLINTON BALDWIN.
